UNITED STATES PATENT OFFICE.

EMILIO CASTIGLIONI, OF DETROIT, MICHIGAN.

DESIGN FOR AN ICE-CREAM CONE.

Application filed November 3, 1923. Serial No. 7,671. Term of patent 3½ years.

To all whom it may concern:

Be it known that I, EMILIO CASTIGLIONI, a citizen of the United States, residing at Detroit, in the county of Wayne and State of Michigan, have invented a new, original, and ornamental Design for Ice-Cream Cones, of which the following is a specification, reference being had to the accompanying drawing, forming a part thereof.

The figure is a front elevation of an ice cream cone embodying my design.

I claim:

The ornamental design for an ice cream cone, as shown.

EMILIO CASTIGLIONI.

Witnesses:

REX FRYE,
ETHEL JEDLISK.
